UNITED STATES PATENT OFFICE.

JAMES NUTTALL, OF BURY, ENGLAND.

DOCTOR OR SCRAPER FOR CLEANING THE SURFACES OF CYLINDERS, ROLLS, AND THE LIKE.

1,092,798.

Specification of Letters Patent. Patented Apr. 7, 1914.

Application filed August 5, 1913. Serial No. 783,183.

To all whom it may concern:

Be it known that I, JAMES NUTTALL, a subject of the King of Great Britain and Ireland, residing at Park View, Walmersley 5 Road, Bury, in the county of Lancaster, England, have invented new and useful Improvements in Doctors or Scrapers for Cleaning the Surfaces of Cylinders, Rolls, and the like, of which the following is a 10 specification.

This invention relates to improvements in doctors, or scrapers, for cleaning the surfaces of cylinders, rolls and the like (which I will hereinafter refer to as "cylinders") 15 and has for its object to provide a rigid doctor, or scraper, which will have a very efficient cleaning effect, be self-sharpening and always retain a keen cutting, or scraping edge in use.

20 The present device may be properly used with printing cylinders or as a scraper for removing substances from cylinders of other nature and I do not limit my invention to its use with any particular type of cylinder.

25 I will describe my invention with reference to the accompanying drawing in which—Figure 1, is a side elevation, Fig. 2 a plan, and Fig. 3 a front elevation of one form of doctor, or scraper, according to my 30 invention.

According to my invention I make the doctor, or scraper, 1, with the cutting, or scraping, edge, 2, continuous but formed so that portions 5 thereof act upon the cylinder 35 in different longitudinal lines parallel with the axis of the cylinder, and so that parts 4 which join the said portions also act upon the said cylinder.

My improved doctor, or scraper, 1, is made 40 of metal, or other suitable material, and may be formed with grooves 3 therein, which are at right angles, or other suitable angle, to the axis of the cylinder, these grooves being preferably larger at the top than at the 45 bottom, or vice versa, and being formed on one, or both sides, of the doctor, or scraper, and having any desired depth and shape.

In the accompanying drawing grooves 3 are shown formed in both sides of the doctor, 50 or scraper 1.

The edge 2 of the doctor, or scraper, thus formed, being beveled, or cut or cast, on an incline, as shown in Fig. 1, will, when pressed against the surface of the cylinder, 55 present thereto portions 5 which act upon

the cylinder in different longitudinal lines parallel with the axis of the cylinder and parts 4 which also act upon the cylinder.

The parts 4 of the edge 2 of the doctor, or scraper 1, which join the portions 5 are 60 preferably inclined to the direction of rotation of the cylinder as shown more clearly in Fig. 2 of the accompanying drawing so as to have a shearing action, which will be increased if the doctor, or scraper, be caused 65 to have a reciprocating motion across the surface of the cylinder, parallel with its axis, the doctor, or scraper being thus reciprocated by any suitable reversing mechanism. 70

I wish it to be particularly understood that I do not limit myself to the precise formations of doctor, or scraper, shown in the accompanying drawing as it is obvious that modifications in the formation can be 75 made without departing from the spirit and scope of the invention.

The doctor or scraper may be made of any suitable metal or alloy which should be sufficiently hard to always retain a keen cutting or scraping edge when in use as the wear on the bearing surface continues. 80

In the following claims the term cylinder is to be read as including a cylinder, roll, or the like. 85

What I claim is:—

1. A rigid doctor or scraper for cleaning the surface of a rotating cylinder, said doctor having a continuous scraping edge adapted to lie in contact with the surface of the roller and having portions of said scraping edge adapted to engage the roller simultaneously in planes parallel to the axis of the roller but circumferentially spaced apart, substantially as described. 95

2. A rigid doctor or scraper for cleaning the surface of a rotating cylinder, said doctor having a continuous scraping edge adapted to lie in contact with the surface of the roller and having portions of said scraping edge adapted to engage the roller simultaneously in planes parallel to the axis of the roller but circumferentially spaced apart, together with other portions of said scraping edge engaging the surface of the cylinder and extending between said parallel portions of the edge, substantially as described. 100

3. A rigid doctor or scraper for cleaning the surface of a rotating cylinder, said doctor having its blade grooved to afford a con- 110

tinuous scraping edge adapted to lie in contact with the surface of the roller with portions of its scraping edge engaging the roller simultaneously in planes parallel to the axis 5 of the roller but circumferentially spaced apart, substantially as described.

4. A rigid doctor or scraper for cleaning the surface of a rotating cylinder, said doctor having its blade grooved on both upper 10 and lower faces to afford a continuous scraping edge adapted to lie in contact with the surface of the roller with portions of its scraping edge engaging the roller simultaneously in planes parallel to the axis of the 15 roller but circumferentially spaced apart, substantially as described.

5. A rigid doctor or scraper for cleaning the surface of a rotating cylinder, said doctor having a continuous scraping edge adapt-

ed to lie in contact with the surface of the 20 roller and having portions of said scraping edge adapted to engage the roller simultaneously in planes parallel to the axis of the roller but circumferentially spaced apart, together with other portions of the scraping 25 edge engaging the surface of the cylinder at an incline to the direction of rotation of the cylinder and extending between said parallel portions of the edge, substantially as described.

In testimony whereof I have signed my name to this specification in the presence of 30 two subscribing witnesses.

JAMES NUTTALL.
